United States Patent Office.

JAMES C. EVANS, OF DELAWARE, OHIO.

Design No. 3,655, dated September 7, 1869.

DESIGN FOR A ROAD-SCRAPER.

The Schedule referred to in these Letters Patent and making part of the same.

To all whom it may concern:

I, JAMES C. EVANS, of Delaware, State of Ohio, have invented and produced a new and original Design for Road-Scrapers, of which the following is a specification.

The nature of my invention or design is fully set forth in the accompanying drawings, to which reference is made.

A A represent the sides of the scraper;
B, its bottom;
C, its cutting or forward end; and
D D, its handles.
a a are straps of metal, secured to the sides, as seen in the drawings.

b b are rings or loops, by means of which the scraper is drawn.

The peculiar feature of this design is in the formation of the bottom and forward end of the scraper.

What I claim, therefore, as my invention, is—
The design for a road-scraper, as herein shown.
In testimony that I claim the foregoing as my own, I affix my signature, in presence of two witnesses.

JAMES C. EVANS.

Witnesses:

JOHN S. JONES,
J. HIPPLE.
